United States Patent Office

Des. 191,845
Patented Nov. 28, 1961

191,845

EXPANDED METAL SHEET

William M. Ries, Wheeling, W. Va., assignor to Wheeling Steel Corporation, Wheeling, W. Va., a corporation of Delaware

Filed Mar. 17, 1961, Ser. No. 64,353

Term of patent 14 years

(Cl. D54—2)

FIG. 1.1

I claim:

The ornamental design for an expanded metal sheet, as shown.
